Filed Sept. 5, 1972, Ser. No. 286,474

Term of patent 14 years

Int. Cl. D17—01

U.S. Cl. D56—9

FIG. 1

FIG. 2**FIG. 3**

FIG. 1 is a front, top and right side perspective view of a piano showing our new design;

FIG. 2 is a front elevational view; and

FIG. 3 is a right side elevational view.

The side of the piano not shown is a mirror image of the side shown. The back of the piano is conventional. The pattern vertical lines in parallel spaced relationship in the upper front board, visible in the figures to either side of the music desk, continues uninterrupted behind the music desk.

We claim:

The ornamental design for a piano, substantially as shown and described.
